UNITED STATES PATENT OFFICE.

RAYMOND REHER, OF NEW YORK, N. Y.

SPEED-VARYING DEVICE.

1,220,554.

Specification of Letters Patent. Patented Mar. 27, 1917.

Application filed October 28, 1913. Serial No. 797,752.

To all whom it may concern:

Be it known that I, RAYMOND REHER, a citizen of the United States, residing at New York city, in the county and State of New York, have invented certain new and useful Improvements in Speed-Varying Devices, of which the following is a clear, full, and exact description.

This invention relates to an improvement 10 in power transmitting or driving mechanisms, the object being to provide a device of this character adapted to vary the speed of a driven shaft relative to the driving shaft. To carry out the object of my invention, I utilize the principle of frictional contact thereby obviating the necessity of resorting to gearing.

In the drawings:

Figure 1 is a plan view partly in section 20 of my improvement.

Fig. 2 is a top plan view of the speed changing device.

Fig. 3 is a vertical sectional view, the section being taken on a line 3-3 in Fig. 1.

Fig. 4 is an enlarged longitudinal sectional view taken on a line 4-4 in Fig. 2.

Fig. 5 is an enlarged end view of the speed changing device.

As herein illustrated, my improvement is 30 illustrated as attached to a motor 1, the said improvement consisting of a frictional speed changing driving mechanism 2.

One of the elements of the improvement consists of a conical driving disk 3 secured 35 to the motor shaft 4, another element consists of a driven disk 5 secured to a shaft 6 carrying, in this instance, pulleys 7, 8 and 9.

To transmit power from the disk 3 to the 40 disk 5 I utilize rollers or wheels 10 and 11 carried by a sleeve 12 rotatably mounted on a fixed rod 13 carried by a pivoted frame 14 normally positioned at an angle relative to the axis of the shafts 4 and 6. (Fig. 4).

The frame 14 is pivoted, intermediate the 45 ends thereof, at 15 and 16 in the housing 16. The pivot point or pin 16 may be secured to the housing 17 but the pin 15 is preferably secured to the frame 14 and rotates with it.

To swing the frame 14 I utilize a shaft 18 50 which is rotatably supported by the frame 14 and passes through the end walls of a sliding frame 19 carried by the swinging frame 14. The shaft 18 is threaded at 20,

the adjacent end wall of the slide 19 being 55 threaded to engage the threads 20.

The outer end of the shaft 18 passes through a slot 21 in the housing 17 and is provided with a handle 22.

While the sleeve 12 is rotatably and slidably mounted on the rod 13 it is also rotatably mounted in the hubs 23, 24 of the frame 19 and travels with it, hence when the slide 19 is moved the rollers 10 and 11 will travel with it or longitudinally of the rod 13. The 65 rollers 10 and 11 are preferably made out of leather, rubber or some other similar substance.

As can be seen in Fig. 1, the rollers 10 and 11 bear against the conical surface of the 70 disks 3 and 5, consequently when the disk 3 is rotated motion will be transmitted to the disk 5 and shaft 6 through the rollers 10 and 11. The relative speeds of the shafts 4 and 6 will be dependent upon the position of the 75 rollers relative to the center of the disks. For example, should the rollers 10 and 11 be positioned equally distant from the centers of the two disks the speed of the two disks would be the same. To increase the speed of 80 the disk 5, relative to the disk 3, the roller 10 would be moved away from the center. To decrease the speed of the disk 5, the roller 10 would be moved toward the center. This, of course, is obvious. To slide the 85 frame 19 to alter the position of the rollers, the shaft 18 would be rotated, the threaded portion 20 acting to move the frame.

To swing the frame 14, the handle 22 would be moved from one side of the slot 21 90 to the other. When the handle 22 is moved to the neutral or central position, as shown in Fig. 5, the disk 5 will not rotate as both rollers will at this time be out of contact with the disks.

To hold the frame 14 in any of the three 95 positions I utilize a spring 25 which bears against a cross-head 26 carrying a spring retaining member 27, Fig. 2. The spring 25 forces the retaining member 27 against a 100 pin 28 carried by an arm 29 secured to the pin 15. It is quite apparent that the pressure of the spring 25 upon the pin 28 will hold the frame 14 in any of the three positions, that is to say the forward, reverse or 105 neutral.

I claim as my invention:

1. A frictional driving mechanism con-

sisting of a driven disk and a second disk to be driven, a plurality of rollers interposed between and in contact with said disks so arranged to be oscillated and shifted between said disks for the purpose of increasing and decreasing the speed of the second disk.

2. A frictional driving mechanism consisting of a driven disk, a driving disk and a plurality of rollers mounted upon a common axis between said disks, one of said rollers being in contact with the driven disk, and the other roller being in contact with the driving disk, in combination with means to shift the rollers from one disk to the other for the purpose of changing the speed of the driven disk.

3. A frictional driving mechanism consisting of a driving disk, and a driven disk and a plurality of rollers mounted upon a common axis in a movable support between said disks, one of said rollers being in contact with the driven disk and the other roller being in contact with the driving disk, and means to shift each roller from one disk to the other in combination with means to shift said rollers relative to the centers of their respective disks.

4. A frictional driving mechanism consisting of a driven disk and a driving disk, and a plurality of rollers between and in contact with said disks, and means to change the contact of said rollers from one disk to the other.

35 5. A frictional driving mechanism consisting of a driving disk, a driven disk and a plurality of rollers mounted upon a common axis in a shiftable support between and in contact with said disks, the axis of said 40 rollers being normally positioned at an an-

gle to the axis of said disks, and means to change the positions of said rollers relative to the disks to vary the speed of the driven disk.

6. A frictional driving mechanism consisting of a conical driving disk, a conical driven disk, a movable carrier located between said disks, said carrier being normally positioned in parallelism with a portion of the conical surface of said disks, rollers mounted upon a common axis carried by said carrier contacting with said disks, and means to change the position of the carrier, and rollers carried thereby, relative to the axis of said disks.

7. A frictional driving mechanism consisting of a driving disk, a driven disk, a pivoted frame located between said disks, the axial line of the fixed points of said frame intersecting the axial line of said disks, a slideable carrier carried by said frame, rollers fastened upon a common axis carried by said carrier adapted to contact with said disks, means to slide said carrier longitudinally of said frame, and means to move said frame upon its pivot points to cause said rollers to change position relative to the disks.

8. A frictional driving mechanism consisting of a conical driving disk and a conical driven disk, a shiftable rotatable power transmitting device located between said disks, and means to move said power transmitting device out of contact with said disks.

Signed at New York city this 6th day of October, 1913.

RAYMOND REHER.
